UNITED STATES PATENT OFFICE.

HERBERT V. DROWN, LOUMEY G. TURCOTT, AND MARY A. HARDING, OF BARTON, VERMONT.

HORSESHOE.

No. 894,942.

Specification of Letters Patent.

Patented Aug. 4, 1908.

Application filed March 10, 1908. Serial No. 420,192.

To all whom it may concern:

Be it known that we, HERBERT V. DROWN, LOUMEY G. TURCOTT, and MARY A. HARDING, citizens of the United States, residing at Bar-
5 ton, in the county of Orleans and State of Vermont, have invented certain new and useful Improvements in Horseshoes, of which the following is a specification, reference being had therein to the accompanying draw-
10 ing.

This invention relates to improvements in horse-shoes, and has for its object the construction of a shoe, as a new article of manufacture, formed from a bar or blank, which
15 bar or blank embodies the peculiar structure of the shoe.

Another object of the invention is the construction of a horse-shoe formed from a single-piece or strip of metal, and comprises a
20 minimum number of parts, and which shoe is not only efficient in operation, but also comparatively inexpensive to manufacture.

With these and other objects in view, the invention consists of certain novel constructions, combinations, and arrangements of parts, as will be hereinafter fully described and claimed.

In the drawings: Figure 1 is a view in elevation of the inner edge of the bar or blank prior to folding for forming the shoe. Fig. 2 is a top plan view of the structure depicted in Fig. 1. Fig. 3 is a view similar to Fig. 1, looking at the outer or front edge of the bar or blank. Fig. 4 is a top plan view of the
35 shoe constructed in accordance with the present invention. Fig. 5 is a transverse, sectional view taken on line 5, 5, Fig. 4. Fig. 6 is a sectional view taken on line 6, 6, Fig. 4. Fig. 7 is a fragmentary view, in side elevation, of the shoe, showing the same in an inclined position with the front or toe-calks engaging the ground. Fig. 8 is a fragmentary view, looking at the inner edge of another embodiment of the present invention. Fig.
40 9 is a top plan view of the structure depicted in Fig. 8. Fig. 10 is a view in side elevation, looking at the front edge of the structure depicted in Fig. 8. Fig. 11 is a sectional view taken on line 11, 11, Fig. 8. Fig. 12 is a sec-
45 tional view taken on line 12, 12, Fig. 10.

In forming horseshoes in accordance with the present invention, we employ a peculiarly-constructed bar or blank, comprising a body having an outer, horizontal rim or
50 flange 1, and a rib or bead 2 formed intermediate the outer and inner edges of the body and between the calks 3. The body is pro-

vided with an intermediate beveled face 4, and with an inner beveled edge 5.

It is to be noted that our horseshoe is pro-
60 vided, preferably, with eight calks, which
may be truncated, as calks 3, or pointed as
calks 6, Figs. 8 to 10. The calks are located
on the web of the shoe intermediate the outer
and inner edges to be equal distances from
65 each other; the two calks which form the
heel calks being located at equal distances
from the ends of the heel of the shoe, and the
two calks which form the toe-calks being
formed an equal distance from the center of
70 the toe of the shoe, all of which calks are
braced from either side by said rib 2, which
rib forms a part of the web of the shoe and
is connected with each of the calks.

It will, therefore, be noted that upon the
75 shoe, we have, preferably, provided two heel
calks; two side calks on each side of the shoe
between the heel-calks and the toe-calks, and
the two calks located at equal distances from
the center of the toe of the shoe, which form
80 the toe-calks.

The outer flange 1 forms a strengthening
web the entire length of the shoe, making the
shoe, in cases of extremely light shoes, less
85 liable to spread, and also affording an oppor-
tunity of punching nail-holes or apertures
through said web or flange 1, in order to shoe
a horse having a thin-shelled foot, without
danger of puncturing the foot; the nail-holes
90 in said shoe being ordinarily placed inside of
the rib 2 before mentioned.

The forming of the calks on the shoe in the
position before mentioned gives an equal
bearing the entire distance around the horse's
95 foot. The under surface of the web of the
shoe is beveled, as at 4 and 5, toward the in-
ner edge thereof; the extreme inner, beveled
edge 5 is at substantially an angle of about
sixty degrees, which is a different angle from
100 the bevel of the web or portion 4. Any
means, ordinarily nail-holes or apertures,
may be placed at any point along the web or
beveled portion 4, to afford the most secure
hold upon the foot.

The two angularly-disposed bevels 4 and 5
105 of the body or web of the shoe prevents any
foreign substances remaining in the horse's
foot, such as, for instance, dirt or snowballs
being held thereby by the shoe, as is the case
with the ordinary shoes, commonly in use.

It is to be noted that the highest portion of
the rib 2 is intermediate the outer and inner
edges of the body, and that the calks are also
placed intermediate said edges. Therefore,
110

in cross - section, the shoe is substantially semi-conical shape, and may be sharp or truncated; the convexed face of each calk is on the inner side of the shoe, preventing any 5 angles which will hold snow or dirt, whereas the outer face 7 is formed vertical for producing a gripping or cutting-edge throughout the entire height of the calk, for preventing the horse from slipping. It will also be 10 noted that said outer edges 7 of the calks are formed in the same plane with the outer edge of the rib or ribs 2; the shape of the calks 3 and 6 permits them to sink in the hard 15 surface of the road, thus diminishing the jar upon the horse's foot, and in case of a horse being driven on ice, the advantages over any other shoe, are, first, there are, preferably, eight calks or bearing surfaces, all of which are equal, making eight projections on the 20 shoe to secure a foot-hold, as compared with three of any ordinary shoe; secondly, the shape of the calks of our shoe enable them to be made much simpler than the calks of any other shoe, and still retain all the 25 advantages, as securing a foot-hold for the horse; and, thirdly, the side-calks afford a foot-hold upon uneven surfaces, which the calks of any other shoe would not grasp, because the bearing surface of each calk is upon the same 30 level or plane. A horse wearing our shoe in traveling upon the ice does not chip the ice, and thus allow the foot to slip, but with a shoe involving eight small calks of peculiar shape, as above described, a more firm foot- 35 hold is obtained.

It is to be understood that a shoe constructed in accordance with our invention can be made much lighter than any other shoe, and still have the strength and durability of a heavy shoe, namely, owing to the outer flange and the positioning of the calks and the rib between said flange and the inner edge of the body, as well as the peculiar shape and size of the calks.

45 The lightness of our peculiarly-constructed shoe makes it a practical one for racing, driving, and working purposes.

It will be understood that the shape and size of the shoe enable the horse to travel 50 nearer as nature intended it should than any other shoe, bringing the bottom of the horse's foot nearer the ground and adding much less weight to the horse's foot than an ordinary shoe known to the art. The shape and position of the toe-calks relieve the strain upon the tendons of the horse's leg earlier than in the case of a straight or long horizontal calk, and does not permit the throwing of dirt, as is the case with a long, straight toe-calk.

60 From the foregoing description, it will be understood that the outer flange or horizontal web 2 is of importance, for the reasons specified, and that the comparatively small semi-frusto-conical calks 3 or the semi-frusto- 65 conical calks 6 are of importance, and,

furthermore, the double beveled portions 4 and 5 of the body also act as a guiding means for directing or displacing any substance which might collect in the foot or within the shoe.

70 It will be noted that each calk is provided, upon opposite sides, with a cutting - edge throughout its entire length, which is produced by forming each calk with a straight, flat, front face, thereby making the calk efficient in operation until the same is worn flat, as it will always expose a gripping surface to the ground or ice.

75 What we claim is:

1. As a new article of manufacture, a 80 horseshoe formed from a single-piece of metal and comprising a body portion provided with an outer, horizontal flange and with a rib extending longitudinally of the body and formed between said outer flange and the inner edge of the body, said body provided with a beveled face at its inner edge and with a beveled face between said first mentioned face and the rib, said body provided with a plurality of calks having curved inner faces 85 and formed between the outer flange and the beveled edges and interrupting the rib, and each calk having an outer, vertical, straight face formed in the same plane with the outer face of the rib.

90 2. A horseshoe formed from a single-piece or strip of metal and provided with a series of semi-conical calks formed upon the body and between the ends and between the outer and inner edges, each calk provided with an inner convexed surface converging into the body of the shoe at the lower, inner edge of the calk, and said calk provided with an outer flat face producing cutting-edges upon 95 opposite sides throughout its entire height.

100 3. As a new article of manufacture, a horseshoe comprising a body provided with an outer horizontal web or flange extending its entire length and with a pair of inner, beveled portions extending the entire length 110 of the body, each beveled portion formed at an angle to the other beveled portion, said body provided with comparatively small calks formed between said outer flange or web and between said beveled portions, each 115 calk provided with a rounded inner face and with a flat outer face producing cutting or gripping edges at opposite sides of the calk, and said body provided with a rib between each two calks and the rib formed between 120 the outer flange or web and the inner beveled portion or face.

125 In testimony whereof we hereunto affix our signatures in presence of two witnesses.
